US00D979027S

(12) **United States Design Patent** (10) Patent No.: **US D979,027 S**
Haji et al. (45) Date of Patent: **** Feb. 21, 2023**

(54) **COMBINATION AIR PURIFIER AND SURFACE SANITIZER**

(71) Applicant: **Next Gen Design and Development LLC**, Ferndale, MI (US)

(72) Inventors: **Hadir Haji**, Bloomfield Township, MI (US); **Taylor Spencer**, Rochester Hills, MI (US)

(73) Assignee: **NEXT GEN DESIGN AND DEVELOPMENT LLC**, Ferndale, MI (US)

(**) Term: **15 Years**

(21) Appl. No.: **29/762,085**

(22) Filed: **Dec. 15, 2020**

(51) LOC (14) Cl. **23-04**

(52) U.S. Cl.

USPC **D23/364**

(57) **CLAIM**

The ornamental design for a combination air purifier and surface sanitizer, as shown and described.

DESCRIPTION

FIG. 1 is a top perspective view of the combination air purifier and surface sanitizer showing my new design;

FIG. 2 is a bottom perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken lines depict portions of the combined air purifier and surface sanitizer that form no part of the claimed design.

1 Claim, 8 Drawing Sheets
